FINGER GRIP FOR HANDLES OF TOOLS

Russell H. Dell, Stonington, Conn., assignor to
 Bostitch, Inc., Stonington, Conn., a corporation
 of Rhode Island

Application March 18, 1950, Serial No. 150,452

4 Claims. (Cl. 145—61)

1

This invention relates to finger-grips for the handles of tools such as hammers, hammer-tackers and other implements which are gripped in the hand for operation by striking a blow.

The invention is particularly directed to improved latching means for securing resilient grips to the handles of tools or other objects to prevent them from slipping or sliding thereon; while permitting convenient removal of the grips without splitting or otherwise damaging the resilient material from which the grips are constructed.

One object of the invention is to provide improved fastening means for use with tubular or cot-like grips of rubber or the like enclosing the handles of various types of implements whereby to prevent them from sliding thereon and becoming released when a blow is struck.

Another object is to provide latching or fastening means of the type indicated which may be released from the handle by prying up the end of the flexible or resilient grip to permit the grip to be slid off from the end of the handle.

Another object is to provide improved fastening means of the type indicated which may be operated to expand the grip for effecting its removal from the handle without splitting the material or distorting the grip to render it unsuitable for further use.

Another object is to provide fastening or attaching means for the hand-grips of tools or implements adapted to bite into the resilient material of the grip under the pressure of the hand when the tool or implement is gripped therein for operation.

Further objects of the invention are set forth in the following specification which describes a preferred form of construction of the fastening means for the grips with certain modifications therein as illustrated by the accompanying drawings. In the drawings:

Fig. 1 is a side elevational view of a common type of hammer-tacker or staple-driving implement showing its handle enclosed by a resilient grip for holding it to strike its forward end against the work;

Fig. 2 is an enlarged side view showing a portion of the handle with the grip secured thereto by means of the present improved attaching or fastening means;

Fig. 3 is a longitudinal sectional view of a portion of the hammer-handle taken on line 3—3 of Fig. 2 and illustrating the attaching means for the resilient grip applied thereto;

Fig. 4 is a greatly enlarged transverse sectional

2

view through the end of the handle-hammer showing the attaching or fastening means for the grip in detail;

Fig. 5 is a greatly enlarged longitudinal sectional view on line 3—3 of Fig. 2 showing the metal latching-blade with its detent means for fastening the resilient grip to the handle;

Fig. 6 is an enlarged perspective view of the metal latching-blade incorporating the detent means for fastening the resilient grip to the handle;

Fig. 7 is a transverse sectional view of the handle and its enclosing grip;

Fig. 8 is an end view of the tubular grip showing the slots therein for the latching-blade which fastens it to the handle;

Fig. 9 is an enlarged sectional detail view showing the means for engaging the blade with the resilient material of the grip;

Fig. 10 is a longitudinal sectional view similar to Fig. 3 illustrating the method of releasing the detent means of the latching-blade from the handle;

Fig. 11 is a similar view showing the detent means released and the grip partially slid off from the end of the handle;

Fig. 12 is an enlarged side view of a portion of the implement-handle illustrating a modified form of attaching means for the grip;

Fig. 13 is a longitudinal sectional view of this latter modified form of construction of the attaching means;

Fig. 14 is a perspective view of the attaching means or latching-blade embodying the detent means for securing the grip to the handle; and

Fig. 15 is an enlarged longitudinal sectional view of a portion of the handle and grip, shown with the last-mentioned modified form of blade or attaching means for the grip.

Hammer-like tools, such as hammer-tackers for driving nails, staples and the like, are usually constructed of metal, for example steel, with resilient hand-grips applied to their handles so that they may be held more securely in the hand and operated more effectively without slipping, and further to prevent injury to the operator's hand. A common type of resilient grip for the handles of such implements consists in a tubular, cot-like sleeve of resilient material, for example rubber, which is slipped on over the handle. In use, such grips are apt to slip and slide on the handles and in extreme conditions allow the tool or implement to escape from the hand so that it has been a common practice to cement or glue

the grips to the metal handles of the implements.

In certain cases, as for example where the implements are made of sheet-metal with the handles of two cooperating sections held together in overlying relationship, it is necessary to remove the hand-grips to separate the parts for access to the interior in repairing or replacing certain elements of their mechanism. When the resilient grip is glued or cemented in place on the handle it is practically impossible to remove it therefrom without considerable stretching and in some cases splitting the material of the grip so that it becomes damaged and unsuitable for replacement on the handle.

To overcome the above-mentioned difficulties in the use of resilient grips on the metal handles of tools and the like the present invention provides a novel form of attaching means for the grips which prevents them from slipping or sliding on the handles, yet allows them to be readily and conveniently removed therefrom without damage so that they may be replaced to continue in use.

In general, the present invention consists in providing a thin metal blade or latch inserted between the resilient wall of the grip and the metal handle and provided with detent means for holding the grip from sliding or slipping on the handle. Preferably, the end of the blade may have one or more prongs or teeth for biting into the resilient material of the grip to secure the blade thereto, and as a further improvement the terminal portion of the blade may have an outwardly inclined lip to provide an opening in the end of the grip for the insertion of a pointed tool such as a screw-driver for prying the detent means out of engagement with the metal handle. The detent means may take different forms such as a tooth or projection engageable in a slot or opening in the metal handle to cause it to be forced thereinto under the pressure of the resilient material of the grip.

Referring to the present drawings, Fig. 1 illustrates a conventional type of hammer-tracker comprising a two part rectangular metal handle 2 terminating at one end in an enlarged head 3, within which is enclosed the mechanism for feeding and driving U-shaped staples in fastening shingles to roofs, carpets to floors, shades to rollers, labels to cases, and many other similar uses. For providing a firm hold on the handle 2 so that it may be held in the hand in striking blows to drive the staples into the work a resilient finger-grip of tubular form is usually slipped on over the handle to enclose the latter. The grip 5 may be molded from rubber, either natural or synthetic, or constructed of similar relatively flexible material and shaped to fit the hand, as shown in Fig. 7, with ribs or flutes 6 extending longitudinally of its sides. The ends of the grip 5 may be bounded by beads 7 with the surface of the main portion of the grip of generally convex contour to provide a convenient hand-hold thereon.

Referring more particularly to Figs. 3 and 6, the present attaching means is embodied in a relatively flat, metal plate or blade 10 adapted to overlie one side of the tubular handle 2 within the side wall of the grip 5. For this latter purpose the interior side wall of the grip 5 is formed with a longitudinally-extending slot 11 and a narrower slot 12 in one side thereof. The blade 10 is of a width to adapt it to be held in the slot 11 and is provided at one end with an inclined tab or ear 14 projecting into the narrow slot 12. At this end of the blade 10 a narrowed portion projects forwardly and is bent at right-angles to form

a prong or detent-projection 15 for engagement in a transverse slot 16 in the side of the handle 2. The purpose of the upwardly-bent tab or ear 14 is to provide a beveled opening or re-entrant space for the insertion of the blade of a sharp tool such as a screw-driver, see Fig. 10, for prying this end of the blade or latch 10 outwardly to remove the detent-prong 15 from the slot 16 so that the grip 5 may be slide off from the end of the handle 2 in the manner as illustrated in Fig. 11.

To provide a secure connection between the grip 5 and the blade or latch 10, the end of the blade opposite from that formed with the detent-prong 15 may be bent upwardly to provide a holding edge 17 for biting into the resilient material of the grip to prevent the latter from slipping or sliding along the blade, see Fig. 9.

Referring to Fig. 3, usually the forward end of the grip 5 abuts the shoulder 18 formed by the end of the head 3 of the implement to prevent the grip from sliding forwardly on the handle 2 and the edge 17 of the bent end of the blade acts to prevent it from sliding or slipping rearwardly thereof. In this way the grip 5 is securely held and latched to the handle 2 by means of the detent 15 at its outer end. The formation of the bent forward end of the blade or latch 10 engages in the resilient material of the grip 5 at a point midway of the ends of the latter so that the pressure of the hand and fingers surrounding the grip has a tendency to compress the resilient material to maintain the edge 17 of the blade firmly embedded therein.

Figs. 12 to 15 of the present drawings illustrate a modified form of construction of the latch or blade 20 as shown in the perspective view Fig. 14. In this embodiment of the invention the blade 20 has portions in the form of teeth 21 slotted from its lateral edges and bent upwardly in inclined relation to cause these elements to bite into the material of the grip 5, see Figs. 13 and 15, so as to prevent the grip from sliding forwardly on the handle 2. This form of construction may be used when the grip 5 is to be applied to the handle of an implement in a position displaced rearwardly from the head of the latter. That is to say, where the forward end of the grip does not abut any shouldered formation on the handle to hold it from sliding forwardly the blade 20 may be used to resist its movement in that direction; the blade 20 being otherwise of the same shape and formation as the blade 10 first described.

With either form of construction of the blade or latch-element 10 or 20 the resilient grip 5 is securely held from sliding on the handle yet, when occasion requires, it may be easily removed therefrom by prying the detent end of the blade upwardly to release the detent-prong 15 for the holding slot 16 as shown in Fig. 10. With the present improved latching means grips of various types and formation may be secured firmly to the handles of different implements while also being adaptable for use with other articles. For example, the latch may be constructed of arcuate form in cross-section to adapt it to be used for fastening the grips of bicycles to tubular handle-bars. Other uses may suggest themselves, for example for fastening grips to the handles of mowing machines or other articles in which such a form of handle is employed.

It is to be understood that while the invention is herein shown in a preferred form of construction with one modification thereof, other variations may be made in the construction of the latching device without departing from the spirit or scope

of the invention as expressed in the following claims. Therefore, without limiting myself in this respect, I claim:

1. In combination with a handle member having a resilient grip of rubber or like material enclosing the same, means for securely fastening the grip from displacement on the handle consisting in a metal latch embedded in the material of the grip and provided with detent means engaging a slot in the handle, said latch formed with a tab at its end projecting upwardly in inclined relation at the side of the detent means to provide for the insertion of an instrument into the end of the grip to pry the detent means out of its holding slot.

2. Latching means for attaching grips to the handles of tools, implements and other articles, in combination with a resilient tubular grip of rubber or the like surrounding said handle, said grip formed with a longitudinally-extending recess in its inner wall, a latch metal extending longitudinally inside the recess in the wall of the grip and provided with a portion of the metal inclined upwardly from the end of the latch for engaging in the material of the grip to hold the latch from sliding therein, detent means on said latch engageable in an opening in the handle to securely hold the grip from sliding on said handle, and a portion of the metal at the end of the latch projecting upwardly to provide a space thereunder for the insertion of an instrument for prying the latch upwardly from the handle to release the detent means.

3. Latching means for attaching resilient grips in place on the handles of tools or other articles, said latching means comprising a metal blade formed with a projecting portion adapted to bite

into the resilient material of the grip on the interior thereof, said blade extending longitudinally of the handle and embedded in the wall of the grip, a detent-projection at one end of the blade engageable in a slot in the handle to hold the grip from sliding or slipping on the handle, and a portion of the metal of the blade adjacent the detent-projection projecting upwardly to provide a space thereunder for the insertion of an instrument to pry the end of the blade upwardly and release the detent-projection.

4. In combination with a tool having a handle, a resilient tubular grip enclosing said handle and provided with a longitudinally-extending slot in its interior wall, a latch in said slot consisting in a relatively flat metal blade having a portion of the metal inclined upwardly from its face for engagement with the interior wall of the grip and a pair of adjacent teeth spaced from its inclined portion, one tooth extending downwardly to form a detent-projection for engagement in a slot in the handle and the opposite adjacent tooth inclined upwardly to provide a space above the detent-projection for the insertion of a tool to pry said detent-projection out from the slot in the handle.
